UNITED STATES PATENT OFFICE.

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed February 16, 1920. Serial No. 358,927.

To all whom it may concern:

Be it known that I, MILTON TIBBETTS, a citizen of the United States, and resident of Detroit, Wayne County, State of Michigan, have invented certain new and useful improvements in Hydrocarbon Motors, of which the following is a specification.

This invention relates to hydrocarbon motors, and particularly to fuel feeding means therefor.

The Stewart vacuum operated feed tank is well known in the hydrocarbon motor industry. One form of such tank is shown in Patent No. 1,158,924 to Webb Jay, dated November 2, 1915. This invention contemplates the use of the type of tank described in said patent and the vacuum operated float means of that patent is illustrated in this application.

20 The present invention is particularly designed for use with a hydrocarbon motor having a carburetor of any desired form using liquid fuel, and having also a fuel heater device using a mixture of gasoline 25 or other liquid fuel and air for its operation, such heater devices being known generally as "combustion heaters".

One of the objects of the present invention is to provide a fuel feeding device 30 adapted to feed liquid fuel to the motor carburetor and at the same time to feed a combustible mixture to a combustion heater such as is referred to above.

Another object of the invention is to provide a fuel feeding device in which there are 35 two feed tanks or chambers from which fuel may be drawn for the motor. Preferably, one of these tanks or chambers feeds liquid fuel only and the other feeds fuel and air.

40 Other objects and advantages will appear from the following description taken in connection with the drawing which forms a part of this specification, and in which the figure represents a vertical section through 45 a fuel feeding device embodying the invention.

Referring to the drawing, 10 represents a primary chamber or a float chamber or tank similar to the inner tank of the well known 50 Stewart vacuum supply tank. This tank 10 is preferably formed of sheet metal and is secured as by screws 11 to a top 12, which may be a casting, as shown. A pipe 13 supplies liquid fuel from a supply tank, which 55 is usually situated some distance lower than

the tank 10 so that a certain amount of vacuum or suction is required to draw the fuel upwardly through the supply pipe 13. The pipe 13 opens into the tank 10 at 14.

The primary tank 10 is also connected 60 with the motor intake pipe above the throttle by means of a pipe 15, communication through the cover 12 being by means of a port 16 which is controlled by a valve 17. The tank is also vented to the atmosphere 65 through a pipe 18 and a port 19, which latter port is controlled by a valve 20.

Thus when the valve 17 is open and the valve 20 is closed, the engine suction is permitted to effect a reduction of pressure within the primary tank 10, causing a flow of fuel through the pipe 13 into the tank 10 and causing the float 21 therein to rise. The float is connected, however, by a lever 22 and link 23 to an arm 24 fulcrumed co- 70 axially with a lever 25 and serving to support one end of a tension spring 26 whose opposite end is connected to the outer end of said lever 25. The spring 26, thus tending to fold the members 24 and 25 toward 75 each other, either above or below their fulcrum, serves to resist the rise of the float 21, since it would cause an unfolding of said members and the rise of the float is consequently delayed until the buoyant force of 80 the constantly incoming liquid is sufficient to overcome the effect of the spring 26. The float then rises suddenly to its upper limit of movement, throwing the parts to the positions indicated in full lines in the drawing. 85

The pull of the spring 26 causes sufficient upward swing of the lever 25 to unseat the air valve 20 and to seat the valve 17, thus cutting off the engine suction and restoring atmospheric pressure within the chamber 10. 90

This permits the fuel accumulated in the chamber to flow out at the bottom past a flap valve 27 arranged in the outlet pipe 28

threaded into the bottom of the tank 10. 95

Usually in the Stewart type of vacuum feeding device, the fuel flows from the float chamber directly into a feed tank which supplies the motor carburetor. In the present invention, however, there is an intermediate tank or chamber 29 which is shown as surrounding and as somewhat larger than the primary tank 10, and the fuel from the tank 10 flows into this second or intermediate tank 29. The tank 29 is also secured to the top 12 which is extended 100

110

yond the tank 10 for the purpose, and it is supplied with air through an air vent 30 shown at the left of the figure.

- The tank 29 has an outlet 31 which is in the form of a stand-pipe extending up from the bottom of the tank to some distance above the bottom of the tank 10 so that the fuel will not flow out of the tank 29 until it rises above the top of said stand-pipe.
- Surrounding both of the tanks 10 and 29, and secured to the top 12, as are those tanks, is a third tank 32 which is the carburetor feed tank. A series of bolts 33 extend through the top 12 and through the flanges 15 of the tanks 29 and 32, thus securing those tanks to the top. The tank 32 is also vented to the atmosphere through a passage 34 formed in the top and communicating with the vent pipe 18 above referred to. The outlet from the tank 32 is shown in the form of a pipe 35 which leads to the usual motor carburetor.

It will be seen that in the normal operation of the device, the fuel will pass from the primary tank 10 into the intermediate tank 29, and so much of it as overflows the stand-pipe 31 will pass into the feed tank 32 thus supplying the motor carburetor with fuel, and under these conditions there will 30 always be maintained a level of liquid fuel in the intermediate tank 29 approximately at the top of the stand-pipe 31 as shown in the drawing. Of course, under some conditions, if the motor is idling for sometime 35 and thereby using very little fuel but is creating a high vacuum in the intake header above the throttle, the operation of the mechanism in the primary tank 10 may cause the fuel in the feed tank 32 to rise 40 slightly above the top of the stand-pipe 31 and consequently the level in the intermediate tank will also be somewhat above the top of the stand-pipe. However, this is not a usual condition and a slight rise in the 45 level in the intermediate tank is of little consequence.

For the purpose of supplying a mixture to a combustion heater or other similar device on the motor, a carburetor 36 is mounted 50 in the cover 12. This carburetor is of the compensating type and draws both fuel and air from the intermediate tank 29. Said tank is adapted for this purpose because of the substantially constant level of liquid 55 fuel therein, and as the small carburetor herein contemplated uses very little fuel, the level in the tank 29 will not fluctuate to any extent between the dumping operations of the primary tank 10.

The carburetor 36 above referred to extends from the top 12 downwardly into the tank 29 nearly to the bottom thereof. This downward extension is in the form of a tube 60 or well 37 having air openings 38 near its upper end and having a telescoped inner tube

39 which is open through a restricted port 40 to the fuel near the bottom of the tank 29. There are a series of transverse ports 41 in the inner tube 39 and near the lower part thereof, thus providing communication between the interior of said tube 39 and the well 37. The tube 39 extends upwardly to outlet ports 42 at a restricted part 43 of an air passage which surrounds the upper part of the tube 39. This air passage 75 receives air from the upper part of the tank 29 through ports 44 and passages 45. The mixture produced at the restricted passage 43 is carried into a pipe 46 which leads to the combustion heater.

From the above it will be seen that the carburetor 36 is an integral part of the fuel feeding device and withdraws both liquid fuel and air from one of the tanks of the device. At the same time the feed of liquid 85 fuel to the motor carburetor is in no way interfered with.

A specific embodiment of the invention has been described in detail and will be specifically claimed, but it will be understood that the invention is not limited to the exact details of construction shown, as it will be apparent that changes may be made without departing from the spirit or scope of the invention.

Having thus described my invention, what I claim and desire to secure by Letters Patent is:

1. A fuel feeding device comprising a float chamber and means for supplying liquid fuel thereto, a chamber connected to the outlet of said float chamber and having a continuously open overflow outlet, and a feed chamber connected to receive the overflow from the second chamber and having a feed outlet at the bottom.

2. A fuel feeding device comprising a chamber and means for feeding fuel thereto, a second chamber surrounding the first chamber and adapted to receive fuel therefrom, said second chamber having an overflow some distance above its bottom, and a third chamber surrounding the other chambers and adapted to receive the overflow from the second chamber, the second chamber and its overflow being the sole means of communication between the first and third chambers.

3. A fuel feeding device comprising a primary chamber having means for feeding fuel thereto, two chambers adapted to receive fuel from said primary chamber, and means for withdrawing fuel from said two receiving chambers.

4. A fuel feeding device comprising a primary tank and vacuum means for supplying fuel thereto, said tank having a valve outlet at its bottom, an intermediate tank adapted to receive the fuel from the primary tank and having a stand-pipe therein, a feed

1. tank connected to receive the overflow of fuel through said stand-pipe, and a carburetor extending into said intermediate tank and adapted to draw fuel and air therefrom.
5. In a fuel feeding device, the combination with a primary tank having vacuum operated means therein for supplying the tank with liquid fuel, an intermediate tank adapted to receive the fuel from said primary tank and having an outlet above the bottom of the primary tank, and a feed tank adapted to receive the overflow from the intermediate tank, said feed tank having its sole communication with the primary tank through said intermediate tank and its outlet.
6. In a fuel feeding device, the combination with a primary tank having vacuum operated means therein for supplying the tank with liquid fuel, an intermediate tank adapted to receive the fuel from said primary tank and having an outlet above the bottom of the primary tank, a feed tank adapted to receive the overflow from the intermediate tank, and a carburetor extending into the intermediate tank and adapted to draw fuel and air therefrom.
7. In a fuel feeding device, the combination with a primary tank having vacuum operated means therein for supplying the tank with liquid fuel, an intermediate tank adapted to receive the fuel from said primary tank and having an outlet above the bottom of the primary tank, a feed tank adapted to receive the overflow from the intermediate tank, and a carburetor having a fuel well extending into the intermediate tank below the liquid level therein.
8. In a fuel feeding device, the combination with a feeding tank having a top to which it is secured and having a fuel outlet at its bottom, an intermediate tank also secured to said top, said top having air vents for both of said tanks, a float tank also secured to said top and having an outlet into said intermediate tank, and means for supplying said float tank with liquid fuel.
9. In a fuel feeding device, the combination with a tank having vacuum operated fuel supply means, and means for withdrawing liquid fuel from said tank, of a carburetor extending into said tank and adapted to draw fuel and air therefrom. 50
10. In a fuel feeding device, the combination with a tank having vacuum operated fuel supply means, of means for withdrawing liquid fuel from the bottom of said tank, and a carburetor extending into said tank and adapted to draw fuel and air therefrom. 55
11. In a fuel feeding device, the combination with a tank having a vented compartment and having vacuum operated fuel supply means, of means for withdrawing liquid fuel from the bottom of said tank, and a carburetor supported on top of said tank and adapted to withdraw mixture therefrom. 60
12. In a fuel feeding device, the combination with a tank having a vented compartment and having vacuum operated fuel supply means, of means for withdrawing liquid fuel from the bottom of said tank, and a carburetor, independent of said fuel withdrawing means, connected to said tank to withdraw fuel therefrom by the action of the carburetor. 70
13. In a fuel feeding device, the combination with a tank and a vacuum operated fuel supply means therefor, of means for withdrawing liquid fuel from the bottom of said tank, and a carburetor acting independently 75 of said fuel withdrawing means and connected to be supplied by said tank at a level of liquid fuel therein. 80
14. In a fuel feeding device, the combination with a tank and vacuum operated fuel supply means therefor, of means for withdrawing liquid fuel from the bottom of said tank to supply a main carburetor, and an auxiliary carburetor so mounted and connected to said tank that it is supplied with 85 liquid fuel at a fuel level in said tank.

In testimony whereof I affix my signature.

MILTON TIBBETTS.
